MERCURY SWITCH WITH ALIGNMENT
RESPONSIVE MEANS

Paul L. Betz, Baltimore, Md., assignor to Consolidated Gas Electric Light and Power Company of Baltimore, Baltimore, Md., a corporation of Maryland

Application July 22, 1948, Serial No. 40,123

5 Claims. (Cl. 200—152)

1

This invention relates to mercury switches of the tiltable container type, and more particularly to such mercury switches provided with means whereby they can be energized only when properly installed.

Mercury switches of the type employing a tiltably mounted container, such as a tube, have attained commercial importance in relay, thermostat and other devices. When such a device is in one operating position the mercury container is tilted to establish an electrical circuit by causing a flow of mercury to bridge electrodes located near one end of the container, while in another operating position the circuit through these electrodes is interrupted due to the tilting of the container in the opposite direction to cause flow of the mercury away from the electrodes. Where such mercury switches are incorporated in devices that provide for a relatively large angular movement of the tiltable container, no complications are likely to be encountered. But such mercury switches possess advantages which render them desirable for use in other classes of devices, as thermoelectric and electronic relay devices, wherein the energy input is so limited that only a relatively small angular movement of the container may be obtained. In the latter type of device proper electrical circuit control by the mercury switch under the operating conditions of limited energy input requires accurate positioning of the switch, as otherwise it is possible for the device to be so installed that the maximum amount of angular movement of the container obtainable from its actuating means operating on limited energy input is insufficient to effect the desired flow of mercury out of and into contact with the electrodes. Also, in sensitive thermostatic devices suitable for operation over a narrow temperature range, as by bimetallic or vapor pressure means, substantially accurate physical positioning of the device, and hence of the tiltable mercury switch, is also necessary to insure agreement between the actual temperature control point of the device and the nominal temperature control point indicated on the adjustable pointer and scale arrangement of the device.

It is an object of this invention to avoid the difficulties above referred to and provide an improved mercury switch of the tiltable container type wherein the switch is rendered ineffective if it is not properly installed.

Another object of this invention is to provide a mercury switch of the type characterized which is particularly sensitive for use with actuating de-

2

vices having available only relatively small energy for operating the switch.

Another object of this invention is to provide an improved mercury switch of the tiltable container type, such as may be operated by a suitable relay or thermostat, having connected therewith a second mercury switch which requires the proper installation of the switch as a unit before the circuit can be controlled through said first named or main switch.

Another object of this invention is to provide an improved mercury switch of the type last characterized wherein the second referred to mercury switch is of improved construction so as to afford increased sensitiveness.

Another object of this invention is to provide an improved mercury switch of the type hereinabove characterized which is simple in construction and certain in operation.

20 Other objects will appear as the description of the invention proceeds.

Stated generally, the improved mercury switch of the present invention includes a main mercury switch of any suitable construction and operable 25 by any suitable device, such as a relay or a thermostat, associated with a frame or housing or other suitable support that has rigidly attached thereto a second mercury switch which is electrically connected with the first named switch 30 and so constructed that, only when the mercury in the second named switch is in a central position, can the main mercury switch, actuated by its actuating device, control the electrical circuit. Thus, failure to install the mercury switch 35 as a unit in proper position results in the controlling of the electrical circuit at the second referred to mercury switch, which is sometimes herein referred to as an alignment responsive switch, and as the latter switch is electrically 40 connected with the main mercury switch, control of the electrical circuit is assumed by the alignment responsive switch rather than by the main switch. Therefore, the inoperativeness of the device as a whole calls attention to the fact that 45 an improper installation has been made.

The invention is capable of receiving a variety of mechanical expressions one of which has been illustrated on the accompanying drawing, and therefore it is to be expressly understood that 50 the drawing is for purposes of illustration only and is not to be construed as a definition of the limits of the invention, reference being had to the appended claims for that purpose.

In the drawing, which is a somewhat schematic elevation view, partially in section, of a mercury

switch embodying the invention, 10 designates any suitable actuating device for a mercury switch, here shown as in the form of a relay comprising an electromagnet 11 and a movable core member 12 which is operatively connected, as by a pivot 13, to a plate 14 pivotally mounted at 15 in any suitable way and on any suitable support. The electromagnet 11 is shown as provided with leads 16 for connection to any suitable source of electrical energy.

Mounted on the plate 14 in any suitable way, as by a clip 17, is a main mercury switch of the tilttable type and which also may be of any suitable construction, being shown as in the form of a tube 18 having a pair of electrodes 19 and 20 projecting into suitable wells 21 formed in the wall of the tube 18 and also including a pool of mercury 22. When the mercury 22 is at one end of the tube 18 as illustrated in the drawing, the electrodes 19 and 20 are bridged thereby and the circuit through the electrodes is closed. The position of the parts as shown in the drawing corresponds to the case where the leads 16 are energized and the resultant downward movement of the core member 12 causes plate 14 to be turned in a clockwise direction about its pivot 15 to establish a closed electrical circuit through said electrodes 19 and 20. Upon de-energizing the leads 16, the core member 12 under the action of a spring or other suitable means is moved upwardly as viewed in the drawing to tilt the tube 10 in a counterclockwise direction about its pivot 15, whereby the mercury 22 moves away from the electrodes 19 and 20 to interrupt the electrical circuit therethrough.

The details of the tubular mercury switch as so far described, and also the relay for operating the same, constitute no part of the present invention, as any suitable switch and actuating means therefor may be employed. Similarly, the pivotal mounting plate 14 for the tilttable switch member 18 may be constructed in any other suitable way—for example, it may be counterbalanced so as to compensate for the unbalance arising from the construction illustrated.

In conformity with the present invention a second mercury switch, or alignment responsive switch, having its axis in suitable relationship to the axis about which switch 18 moves is rigidly mounted on the before mentioned support, here shown as a frame or housing 23, this second switch being electrically connected with the mercury switch 18. As illustrated somewhat diagrammatically in the drawing, this second mercury switch includes a suitable envelope 30, preferably in the form of a tube, and a pair of sealing members 31, disposed intermediate the ends of the tube 30 so as to be relatively remote therefrom. Sealing members 30 carry probe-like members 32 and 33 suitably sealed into said envelope, said members 32, 33 preferably depending into the tube so as to project downwardly across the major portion of its diameter and to be in position to pass through the surface of a mercury pool 34. Mercury pool 34 is of suitable size and so disposed within the tube 30 that it bridges the members 32 and 33 when the tube 30 is in substantially a horizontal position. In the illustrated embodiment, members 32, 33 are made a part of the electrical circuit and serve as electrodes which cooperate with mercury pool 34 so that when tube 30 is in substantially a horizontal position a continuous electrical path is provided. Other physical arrangements of the alignment responsive switch 30 may be employed if desired,

but the illustrated arrangement is preferred inasmuch as greater sensitivity to angular displacement is obtained where, as shown, the electrodes are positioned medially of the tube 30 so as to be not only adjacent to each other but also relatively remote from the ends of the tube 30, depending into a position wherein their extremities are submerged in the pool of mercury 34. Tube 30 may be rigidly mounted on the frame or casing 23 in any suitable way as by a pair of clips 35.

Any suitable means may be provided for connecting the probe-like members or electrodes 32 and 33 in series with the electrodes 19 and 20. As illustrated, terminal blocks 40, 41 and 42 of any suitable construction are mounted on the frame or housing 23 in any suitable way, and a flexible connection 43 is provided between the electrode 19 and the terminal block 40, a flexible connection 44 is provided between the electrode 20 and the terminal block 41, and connectors as wires 45 and 46, which may be flexible or rigid, are provided between the terminal block 40 and electrode 32 and between the terminal block 42 and the electrode 33, respectively. The terminal blocks 41 and 42 also have any suitable provision for attaching thereto at 47 and 48 the leads from the circuit which is to be controlled by the switch 18.

The complete electrical circuit to be controlled by switch 18 therefore extends from input lead connection 47 on terminal block 41 through flexible connection 44, electrode 20, mercury pool 22, electrode 19, flexible connection 43, terminal block 40, wire 45, electrode 32, mercury pool 34, electrode 33, wire 46 and back to the other input connection 48 on terminal block 42. When the frame or housing 23 is properly installed so that the tube 30 is in a substantially horizontal position the circuit from the terminal blocks 41 and 42 to the electrodes 19 and 20 is complete through the electrodes 32 and 33 by means of the mercury pool 34. Thereby the opening and closing of said circuit may be effected by the operation of the mercury switch 18 under the control of the relay 10. On the other hand, if the unit is not installed properly, so that the tube 30 is not in a substantially horizontal position, the circuit through the electrodes 32 and 33 is interrupted by the mercury pool 34 moving to one end or the other of the tube 30. Thereby the circuit is broken between the terminal block 42 and the electrode 19. Under these conditions the mercury switch 18 is rendered inoperative notwithstanding energization and de-energization of the relay 10, so that warning is given that the installation is improper and appropriate correction must be made.

In general, the operating characteristics of the relay, thermostat or other actuating device 10 together with its associated mercury switch 18 and the operating characteristics of the alignment responsive switch must be coordinated to assure that under conditions of improper horizontal positioning of the alignment responsive switch and hence housing 23 the electrical circuit between the terminals on blocks 41, 42 will be controlled by the alignment responsive switch rather than by the main switch 18. Thus, for example, in the embodiment as illustrated in the drawing the angular displacement between the horizontal and the make or break positions of the switch 18 effected by the relay 10 is, as a matter of practice, made greater than the angular displacement from the horizontal required to just make or break the circuit through the electrodes 19 and 20, the additional angular displacement being

provided as a factor of safety to nullify slight errors of installation. However, as will be apparent, errors of installation exceeding the foregoing excess capacity for angular displacement will result in the actuating device 10 being unable to move the switch 18 through an angle sufficient to properly make or break the circuit through the electrodes 19 and 20. To provide the safety feature of the present invention the angular displacement at the horizontal tube 30 required to break the circuit between the electrodes 32 and 33 must not exceed the difference in angular displacement between the actual displacement from the horizontal of which switch 18 is capable and the minimum displacement of switch 18 required to make and to break the circuit whichever difference is smaller. If the minimum displacement of switch 18 from its closed position required to open the circuit through its electrodes is different from the minimum displacement from its open position required to close said circuit, the angular displacement from the horizontal of the switch 30 required to break the circuit through the electrodes 32 and 33 must not exceed the smaller of the differences in angular displacement between the total actual displacement of the switch 18 effected by the relay 10 and the minimum displacements of said switch required to just open and just close the circuit, i. e., to just reverse the circuit condition through switch 18 from the open and closed positions.

When the device shown in the drawing is installed improperly the alignment responsive switch will cause the electrical circuit conditions between terminal blocks 41 and 42 to assume the condition that would normally obtain with proper alignment when electromagnetic device 11 is de-energized. Thus, under normal conditions de-energizing device 11 causes the circuit between terminal blocks 41 and 42 to be open. Therefore, the alignment responsive switch 30 is so arranged as to open the circuit between the terminal blocks 41, 42 under conditions of improper alignment of the device.

I am aware that leveling switches have heretofore been proposed which include a pair of contiguous electrodes in a common well or closely adjacent wells at one end of a container, but experience has demonstrated that such switches lack the sensitivity required for providing the before described safety feature where the mercury switch to be controlled is actuated by a relay, thermostat or other actuating device for which only relatively small energy is available.

It will therefore be perceived that the present invention provides an improved mercury switch of the tiltable type which has in circuit therewith a mercury switch of high sensitivity so that slight displacement of the switch as a unit for its proper position will result in rendering the main mercury switch ineffective as a circuit controlling member and thereby give warning that the installation is improper. Thereby mercury switches of the tilting type may be used satisfactorily with relays, thermostats and other actuating devices notwithstanding that the energy available is quite limited, whereby tiltable mercury switches may be used with such devices without the difficulties heretofore encountered in assuring proper installation in order that such actuating devices shall satisfactorily effect the opening and closing of the circuit to be controlled.

While the embodiment of the invention illustrated on the drawing has been described with considerable particularity, it is to be expressly

understood that the invention is not limited thereto, as the same is capable of receiving a variety of other expressions as will now be apparent to those skilled in the art. While a particular mercury switch of the tilting type, acting as a main switch, and a particular electromagnetically operated device functioning as a relay when associated therewith, have been illustrated and described by way of exemplifying the embodiment and operation of the present invention, it is to be expressly understood that the invention is not limited thereto as tilttable mercury switches of other constructions, and other forms of actuating devices therefor, may be used in embodying the present invention without departing from the spirit thereof. Also, while a preferred form of alignment responsive switch has been described with considerable detail, such alignment responsive switches may take other forms without departing from the broader aspects of this invention as will now be apparent to those skilled in the art. Reference is therefore to be had to the claims hereto appended for a definition of the invention.

25 What is claimed is:

1. In a device of the character embodying two mercury switches connected in series in a circuit to be controlled, the combination of a common switch support normally occupying a fixed position in space, a first mercury switch movably mounted on said support, a controlling circuit, means responsive to changes in the electrical energy conditions in said controlling circuit for repeatedly moving said first switch between open and closed positions, and a second mercury switch connected in series with said first switch and fixedly mounted on said support and held in a fixed position in space when said first switch is moved, said second switch including a tubular envelope, a mercury pool in said envelope and a pair of electrodes positioned adjacent one another near the middle of said envelope, the circuit through said electrodes being closed continuously by said mercury pool when said support is properly installed with the envelope of said second switch in a horizontal position, and being open continuously when said support is installed improperly with the envelope of said second switch misaligned with respect to the horizontal.
2. In a switch device of the character described, a support adapted to occupy a fixed position in space, a first mercury switch tiltably mounted on said support having a pair of electrodes connectable to a circuit to be controlled, means including a relay responsive to the electrical energy conditions in a controlling circuit for repeatedly tilting said first switch back and forth between one position of rest wherein the circuit through said electrode is closed by the mercury of said switch and a second position of rest wherein the circuit through said electrodes is open, and a second mercury switch having electrodes connected in series with the electrodes of said first switch and fixedly mounted on said support, said second switch including a pool of mercury which continuously completes the circuit through the electrodes thereof when said support occupies the desired fixed position in space but flows away from said electrodes and opens said circuit when the support is angularly displaced with respect to said desired position.
3. A switch device as claimed in claim 2 wherein the desired fixed position in space of said support is such as to maintain the second switch in

an approximately horizontal position, and wherein said second switch is so constructed and arranged that it will open the circuit through the electrodes upon an angular displacement thereof with respect to the horizontal of less magnitude than the smaller of the angular differences between the total actual angular displacement of said first switch when tilted from one of its rest positions to the other and the minimum angular displacements of said first switch from said rest positions required to just reverse the circuit condition through its electrodes.

4. In a switch device of the character described, a support adapted to occupy a fixed position in space, a first mercury switch comprising a tubular envelope tiltably mounted on said support, a mercury pool in said envelope and a pair of electrodes connectable to a circuit to be controlled, means responsive to the electrical energy conditions in a controlling circuit for repeatedly 15 tilting the envelope of said first switch back and forth between one position of rest wherein the circuit through said electrodes is closed by the mercury pool and a second position of rest wherein the circuit through said electrodes is open, and a second mercury switch fixedly mounted on said support and including a tubular envelope, a pair of electrodes positioned adjacent one another near the middle of said envelope connected in series with the electrodes of said first switch 20 and a mercury pool for bridging said electrodes.

said mercury pool continuously completing the circuit through the electrodes of said second switch when said support occupies the desired fixed position in space but flowing away from said electrodes and opening said circuit when the support is angularly displaced with respect to said desired position.

5. A switch device as claimed in claim 4 wherein the angular displacement of said support required to open the circuit through the electrodes of said second switch is less than the difference between the total angular displacement of said first switch when tilted from one of its at-rest positions to the other and the minimum angular displacement of said first switch from either of said at-rest positions required to just reverse the circuit condition through its electrodes.
